ATTORNEY

UNITED STATES PATENT OFFICE.

MANIE OLSON, OF MOUNT VERNON, WASHINGTON.

CABLE-CLAMP.

1,256,824.

Specification of Letters Patent. Patented Feb. 19, 1918.

Application filed April 9, 1917. Serial No. 160,794.

To all whom it may concern:

Be it known that I, MANIE OLSON, a citizen of the United States, residing at Mount Vernon, in the county of Skagit and State 5 of Washington, have invented certain new and useful Improvements in Cable-Clamps, of which the following is a specification.

This invention relates in general to cord and rope holders and more particularly to 10 a cable clamp.

The primary object of the invention is to provide a clamp which will efficiently hold a plurality of cables in spaced relation.

Another object is to provide a clamp including a support having a locking key associated in coöperative relation therewith to retain a plurality of cables in a clamped position upon said support.

A further object is to provide a clamp 20 which is so constructed as to firmly grip a cable without mutilating the same.

The above and other objects will be more readily seen from the following description and accompanying drawings.

25 In which drawings:

Figure 1 is a side elevation of my improved clamp showing the application thereof.

Fig. 2 is a top plan view and

30 Fig. 3 is a cross sectional view taken on line 3—3 of Fig. 1.

In the drawings the numeral 1 indicates a block or cable support the configuration of which is substantially similar to that of 35 an inverted cone. It will be noted that the block is formed with a small end 2 and is flared outwardly therefrom to provide a broad upper surface 3 the latter having the inwardly curved retaining arms 4 and 5 positioned on opposite margins thereof. The

40 ends of the retaining members are recessed intermediate the lateral margins thereof as indicated at 6 and shown to advantage in Fig. 2. A centrally disposed tapered recess

45 7 is formed in the block 1 and communicates with an opening provided in the lower end 2. A retaining key 8 is provided which consists of the enlarged head 9 equipped with the depending shank 10, the latter being shaped to be received in the recess 7 and provided with a threaded bore 11 which in assembled position, registers with the opening formed in the lower end of the 50 block. The threaded shank of a bolt 12 is

inserted through the opening formed in the 55 lower end of the block 1 and is adapted to be received in the threaded bore 11 of the key 8. By rotating the bolt 12 the key 9 is slidably adjusted in the recess 7 for the purpose of tightening or releasing the grip 60 on the cables.

In practice, a pair of cables are arranged upon the blocks 1, each cable being positioned beneath one of the retaining members 4 and 5 respectively. The shank of the 65 key 9 is then inserted in the recess 7, and the enlarged head of said key is received in the recesses 6 as shown. The bolt 12 is then inserted in the opening in the lower end of the block, and is properly engaged 70 with the bore 11 of the said locking key. Thus it will be seen by turning the bolt in one direction the enlarged head of the retaining key will be clamped firmly against the cables while operation of the bolt in the 75 reverse direction will release the grip upon said cables.

I have thus fully described the preferred form of my invention but do not limit myself to the exact construction set forth but 80 reserve the right to make such changes as may come within the scope of the claims without departing from the spirit of my invention.

What I claim is:

1. A cable clamp, including a block having a recess formed therein and provided with an opening communicating with said recess, retaining arms formed on said block, a retaining key adapted to be received in 90 said recess, said retaining key being equipped with a bore registering with said opening, and a locking member engaged with the bore of said key.

2. A cable clamp including a block, inwardly curved arms formed on said block and a retaining key adapted to operate between said arms for clamping cables between said key and under said arms.

3. A cable clamp including a block, inwardly curved arms formed on said block, said arms being provided with recessed ends, and a retaining key adapted to operate between said arms and in said recess for clamping cables between said key and under 105 said arms.

4. A cable clamp including a block, inwardly curved arms formed on said block,

said arms being provided with recessed ends, a retaining key adapted to operate between said arms, said key having an enlarged head adapted to be received in said recess in said arms for clamping cables under the curved ends of said arms and the enlarged head of the key.

In testimony whereof I affix my signature in presence of two witnesses.

MANIE OLSON.

Witnesses:

JOHN O. NATTERLUND,
EDWARD OLSON.
